UNITED STATES PATENT OFFICE.

JOSEPH TAGNER, OF NEW YORK, AND WILLIAM MÜNCH, OF RICHMOND HILL,
NEW YORK.

SCUTTLE-COVER OPENER.

1,130,037.

Specification of Letters Patent.

Patented Mar. 2, 1915.

Application filed November 3, 1914. Serial No. 870,075.

To all whom it may concern:

Be it known that we, JOSEPH TAGNER and WILLIAM MÜNCH, both citizens of the United States, and residents of New York, borough of Brooklyn, county of Kings, and of Richmond Hill, county of Queens, and State of New York, respectively, have invented a certain new and useful Improvement 5 in Scuttle-Cover Openers, of which the following is a full, clear, and exact 10 specification.

This invention relates more particularly to a class of devices adapted to be used in buildings and like structures.

15 Our invention has for its object primarily to provide a device or opener designed to be employed in buildings and elsewhere which are constructed with skylights, air shafts, and the like having adjustable covers, doors, 20 or transoms whereby these parts, which are usually at inaccessible locations, may be conveniently raised and lowered for ventilating and other purposes, the invention consisting essentially of a lifting member, 25 or bar having one of its ends pivoted to the cover, and this bar is movably disposed through a supporting casing so as to be directed to different positions for variably raising and lowering the cover as well as 30 serving to hold the cover when in adjusted position.

Other objects of the invention are to provide means adapted to permit the bar to be 35 manually moved from distances thereunder; to provide in the casing a cam operative retainer for holding the bar against movement when positioned; and to provide a rotatably movable weighted lever for operating the 40 retainer.

A further object of the invention is to provide a scuttle cover opener of simple construction, and which is susceptible of being made so as to combine great strength and durability.

45 A practical embodiment of the invention is represented in the accompanying drawing forming a part of this specification in which similar characters of reference indicate corresponding parts in all the views, the said invention being more fully described hereinafter, and then pointed out in the claims at the end of the description.

In the drawing, Figure 1 is a longitudinal 50 vertical section through a skylight with one form of scuttle cover opener embodying

our invention applied thereto. Fig. 2 is an enlarged view, partly fragmentary, taken longitudinally through the casing of the device, and which shows a number of the operative parts thereof, and Fig. 3 is an enlarged sectional view, partly in detail, taken on the line II—II of Fig. 1.

The device, or scuttle cover opener has a substantially rectangular supporting casing 10 provided with two spaced parallel side 65 plates 11 and 12 which are bridged by a top plate 13, and one end of both of the side plates are secured to the support, or base frame, as 14, of the cover, door, or transom, as 15, of a skylight, air shaft, or the like of 70 a building, or other structure, the cover being hinged, as at 16, to the base. As shown, the casing 10 is positioned to extend interiorly of the base frame 14 from a part thereof which is under the free end 75 of the hinged cover 15. The bridging plate 13 is considerably shorter than the side plates 11 and 12, and this bridging plate is spaced some distance from the free ends of the side plates. Extending from the lower 80 part of the side plate inwardly of the casing is a flange 17 of a similar length to the bridging plate so that the outer end of this plate and the flange are on alinement. Between the free ends of the side plates 11 and 85 12 is a plate 18 having its inner edge curved, at 19, and this plate is of a width whereby its curved edge is spaced from the opposed ends of the bridging plate 13 and the flange 17. In this manner a passage 20 is provided 90 through the casing while the curved edge 19 of the plate 18 and the opposed ends of the bridging plate 13 and the flange 17 serve as a guide for a lifting member, or bar 21 which is movably disposed through the passage 20 of the casing 10.

The lifting bar 21 is preferably slightly curved, and this bar may be of any desired length. The upper end of the bar 21 is pivoted, at 22, to the cover 15 at a part 100 thereof opposite to its hinged end, and to the lower end of this bar is connected by a hook or otherwise one end of a line, or cable 23 serving as means to permit the bar to be manually moved, as will be hereinafter 105 more fully explained. The line 23 is guided over a pulley 24 which is rotatably held between the side plates 11 and 12 of the casing 10, and the cable is then allowed to hang a suitable distance below the device and un- 110

der the cover 15 so as to be accessible for operation especially as these covers are generally located at unusual heights. The other end of the cable 23 is attached to one end of a rod, or lever 25 having a ball, or weight as 27, on its other end. The weighted lever 25 is held intermediate its ends to a short shaft 28 of a cam actuated retainer, 29 adapted to hold the lifting member, or bar 28 against movement when adjusted in position in the passage 20 of the casing 10, the shaft being journaled in the side plates of this casing.

The cam actuated retainer 29 consists of a circular disk 30 eccentrically fixed on the part of the shaft 28 within the casing 10, and this cam disk is disposed in an opening 31 of a slidably movable gripping element, or pawl 32 so as to be freely rotatable therein. The gripping element, or pawl 32 is preferably in the form of a substantially square block positioned between the side plates of the casing 10 whereby it may be moved to and from the lifting bar 31. On the edge of the block opposed to the lifting bar are provided two spaced teeth, or substantially cone-shaped extensions 33 and 34 adapted to engage the bar, and to limit the movement of the pawl, or toothed block 31 when forced in a direction from the bar 21 projecting interiorly of the casing 10 from spaced parts of its side plate 12 are two alined stops, as 35 and 36.

The pawl, or toothed block 31 is normally held into engagement with the lifting bar 21 for holding this bar against movement by the weight 27 of the lever 25 tending by reason of its automatic downward movement to revolve the shaft 28 and the cam disk 30 for forcing the pawl into contact with the bar 21, and when the device is operated, for instance, to raise the cover 15 the part of the line 23 which is attached to the lever 25 is manually guided to move the weight 27 of the lever in an upwardly direction. The shaft 28 and the eccentrically revolvable cam 30 will thereby be revolved to force the pawl 31 free from its engagement with the bar 21 and against the stops 35 and 36. By then directing the part of the line which is guided over the pulley 24 and which is attached to the lower end of the bar 21 also in a downwardly direction this bar will be moved upwardly in the passage 20 of the casing 10 for swinging the cover 15 on its hinge to a suitable open position. When the line 23 is released the weight 27 will automatically move in an opposite direction, and the shaft 28, the cam 30, and the pawl 31 will be reversely operated so that the pawl will be forced into engagement with the bar 21 which in turn will be held against accidental movement to hold the cover in an open position. By subsequently pulling the line 23 to operate the lever 25

in a similar manner against its weight the shaft 28 and the cam 30 will be rotatably moved to slidably guide the pawl for engagement with the bar 21, and the weight of the cover will cause it to close on its base at which time the bar 21 will be moved downwardly in the passage of the casing 10. When the line 23 is again released the retainer 29 will also be automatically operated by the lever 25 in the manner above explained to lock the bar against movement, and the cover will in turn be tightly held in a closed position on its base.

In the foregoing description, we have embodied the preferred form of our invention, but we do not wish to be understood as limiting ourselves thereto, as we are aware that modifications may be made therein without departing from the principle, or sacrificing any of the advantages of this invention, therefore we reserve to ourselves the right to make such changes as fairly fall within the scope of the appended claims.

Having thus described our invention, we claim as new and desire to secure by Letters Patent:—

1. In a device of the character described, a lifting bar having one end adapted to be pivoted to the cover of a skylight or the like so as to be opened or closed thereon, a casing adapted to be fastened to the support of the cover, and through which the bar is movably disposed, a shaft journaled in the casing, a lever having its central part held on the shaft, a weight on one end of the lever, and a cam actuated retainer on the shaft, said retainer being normally held in engagement with the lifting bar by the weight of the lever tending toward a downward movement whereby the bar will be held against accidental movement, and the said retainer being released from engagement with the bar when the opposite end of the lever is directed for the weight to move upwardly so that the lifting bar may be forced upwardly to raise the cover from its support.

2. In a device of the character described, a lifting bar having one end adapted to be pivoted to the cover of a skylight or the like so as to be opened or closed thereon, a casing adapted to be fastened to the support of the cover, and through which the bar is movably disposed, a shaft journaled in the casing, a weight on the shaft, a cam actuated retainer on the shaft, said retainer being normally held in engagement with the lifting bar by the weight tending toward a downward movement whereby the bar will be held against accidental movement, means on the weight, adapted to be manually operated to lift the weight to move the retainer from its engagement with the lifting bar, and means on the lifting bar, adapted to also be manually operated to then force the

- bar upwardly to raise the cover from its support.
3. In a device of the character described, a lifting bar having one end adapted to be pivoted to the cover of a skylight or the like so as to be opened or closed thereon, a casing adapted to be fastened to the support of the cover, and through which the bar is movably disposed, a shaft journaled in the casing, a lever having its central part held on the shaft, a weight on one end of the lever, a line connected to the opposite end of the lever and to the other end of the lifting bar, and a cam actuated retainer on the shaft, 10 said retainer being normally held in engagement with the lifting bar by the weight of the lever tending toward a downward movement whereby the bar will be held against accidental movement, and the said 15 retainer being released from engagement with the bar when one part of the line is guided to direct the lever for the weight to be moved upwardly so that the other part of the line may be guided to also force the bar 20 upwardly to raise the cover from its support.
4. A device of the character described, comprising a lifting bar having one end adapted to be pivoted to the cover of a skylight or the like so as to be opened or closed thereon, a casing adapted to be fastened to the support of the cover, and through which the bar is movably disposed, a shaft journaled in the casing, a gripping element eccentrically disposed on the shaft so as to be 25 slidably moved into and out of engagement with the lifting bar whereby the bar will be held against movement, a weight on the shaft tending toward a downward movement 30 to revolve the shaft for normally holding the gripping element into engagement with the lifting bar, means on the weight, adapted to be manually operated to lift the weight for rotating the shaft to free the gripping 35 element from its engagement with the lifting bar, and means on the lifting bar, adapted to also be manually operated to then force the bar upwardly to raise the cover from its support.
5. A device of the character described, 40 comprising a lifting bar having one end adapted to be pivoted to the cover of a skylight or the like so as to be opened or closed thereon, a casing adapted to be fastened to the support of the cover, and through which the bar is movably disposed, a shaft journaled in the casing, a lever having its central part held on the shaft, a weight on one end of the lever, a line connected to the opposite end of the lever and to the other end of the lifting bar, a circular disk eccentrically held on the shaft, a toothed block on 45 the disk, adapted to be slidably moved into and out of engagement with the lifting bar when the disk and the shaft are revolved whereby the bar will be held against movement, and the toothed block being released from engagement with the bar when one part of the line is guided to direct the lever for the weight to be moved upwardly so that the other part of the line may be guided to also force the lifting bar upwardly to 50 raise the cover from its support.

This specification signed and witnessed this second day of November A. D. 1914.
